UNITED STATES PATENT OFFICE.

HERMAN W. HOFF, OF BEAR CREEK, MONTANA.

MINER'S LAMP TOOL.

1,412,745.

Specification of Letters Patent. Patented Apr. 11, 1922.

Application filed November 9, 1921. Serial No. 513,996.

To all whom it may concern:

Be it known that I, HERMAN W. Hoff, a citizen of the United States, residing at Bearcreek, in the county of Carbon and State of Montana, have invented certain new and useful Improvements in a Miner's Lamp Tool; and I do hereby declare the following to be a full, clear, and exact description of the invention, such as will enable others skilled in the art to which it appertains to make and use the same.

The acetylene lamps generally used by miners corrode at the gas outlet and require to be cleaned. This is usually effected by means of a needle.

The present invention provides a tool specially designed for the purpose aforesaid which when not in use may be attached to the clothing, so as to be readily at hand when needed, and which houses the needle to protect it and prevent the same catching into the clothing or other object or injuring the person.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification.

Figure 1 is a side view of a device of the nature aforesaid embodying the invention,

Figure 2 is a central longitudinal section thereof,

Figure 3 is a detail perspective view of the body disassociated from the cooperating parts,

Figure 4 is a detail view of the jaws, and

Figure 5 is a detail view of the needle.

Corresponding and like parts are referred to in the following description and designated in the several views of the drawings by like reference characters.

The needle 1 is tapering and slender and is of polygonal form in cross section, preferably square, to provide cutting edges.

The holder for the needle 1 comprises a body 2 having an intermediate and end portions reduced as indicated at 3 and 4. The end portion 4 is externally screw threaded

and formed with a slot 5 which is adapted to receive the jaws.

The jaws 6 are connected at their inner ends, as indicated at 7, and their outer ends are beveled or tapered to form inclined surfaces whereby to contract the jaws and cause them to grip the needle 1. The jaws are preferably formed of a strip which is doubled upon itself, the fold 7 being sufficiently thin and elastic to normally hold the gripping ends of the jaws spread. When the jaws 6 are in position in the slot 5, their tapering ends project beyond the threaded end 4 of the body 2 so as to ride upon the tapered end 8 of an internally threaded cap 9 mounted upon the threaded end 4 of the body 2. An opening 10 is formed in the tapered end 8 of the cap 9 to receive the needle 1. The external diameter of the cap 9 corresponds with the diameter of the intermediate reduced portion 3 of the body 2, whereby, a casing 11 may slip over the cap 9 and reduced portion 3 and frictionally engage the same whereby to hold the casing in position. The outer side of the casing 11 comes flush with the outer side of the body 2. A safety-pin 12 is applied to the casing 11 and serves as convenient means for attaching the device to the clothing of the miner, whereby the tool may be conveniently at hand when required for use. The casing 11 forms a housing for the needle 1 and prevents injury thereto and the same from catching into an object or injuring the person. When the cap 9 is unscrewed from the reduced portion 4 of the body 2, the gripping ends of the jaws 6 spread, thereby admitting of the needle 1 being placed in position, or removed, as required.

After the needle has been placed in position, the cap 9 is screwed upon the part 4 of the body 2, and its tapered end 8 riding upon the inclined or beveled ends of the jaws 6 compress the latter and cause the same to grip the needle and retain it in place. The use of the tool is well understood. Suffice to state that when the outlet of an acetylene lamp, such as used by miners, becomes corroded or otherwise fouled it may be cleaned by introducing the needle therein and simultaneously advancing and rotating the tool, the sharp corners of the needle acting as cutters to enlarge the outlet.

What is claimed is:

1. A device of the character specified comprising a body having an intermediate and end portions reduced, and having the re-

duced end portion externally screw threaded and formed with a longitudinal slot, jaws disposed in said slot and having their gripping ends projecting and tapered, a screw cap mounted upon the threaded portion of the body and having its outer end made tapering to coact with the tapering ends of the jaws whereby to contract the latter to grip an article placed therebetween, and a casing engaging the screw cap and the intermediate reduced portion of the body and having a safety pin applied thereto.

2. A device of the character specified comprising a body having an intermediate and end portions reduced, the latter being externally screw threaded and formed with a slot, connected jaws disposed within said slot and having their outer ends projecting and made tapering, a screw cap mounted upon the

threaded end of the body and having its outer end tapered to engage the tapering ends of the jaws to contract the latter, the outer side of the screw cap coming flush with the intermediate reduced portion of the body, a needle gripped between the jaws, and a casing housing the needle and engaging the screw cap and intermediate reduced portion of the body by means of a slip joint, said casing being provided with a safetypin whereby the device may be attached to the clothing.

In testimony whereof I affix my signature in presence of two witnesses.

HERMAN W. HOFF.
